CLAIM

The ornamental design for a putting practice guide, as shown and described.

DESCRIPTION

FIG. 1 is a front perspective view of a first embodiment of a putting practice guide showing my new design; FIG. 2 is a left side view of the first embodiment, the right side being identical;

FIG. 3 is a front elevational view of the first embodiment, the rear elevational view being identical;

FIG. 4 is a top plan view of the first embodiment, the bottom plan view being identical;

FIG. 5 is of a front perspective view of a second embodiment thereof;

FIG. 6 is a left side view of the second embodiment, the right side being identical;

FIG. 7 is a front elevational view of the second embodiment, the rear elevational view being identical; and,

FIG. 8 is a top plan view of the second embodiment, the bottom plan view being identical.
